UNITED STATES PATENT OFFICE

2,253,673

AUTOMATIC WATER MOP AND POLISHER

Arvid E. Anderson, Philadelphia, Pa.

Application August 25, 1939, Serial No. 291,821

1 Claim. (Cl. 15—129)

My invention relates to a new and useful automatic water mop and polisher and has for one of its objects to provide an exceedingly simple and effective device of this character which is highly efficient in operation and especially adapted for washing and polishing automobile and other finished or smooth surfaces.

Another object of the invention is to construct a device of this character consisting of a hollow handle unit including a head, and a detachable cap carrying the mop elements and forming with the head a receptacle to hold a cleaning or polishing substance.

Another object of the invention is to provide a mop structure in which a continuous stream of water may be fed thereto in order to keep the mop wet and carry off the dirt as it is loosened by the rubbing or scrubbing operations.

A further object of this invention is to form a detachable cap of unique construction to which the mop elements are attached in a novel and inexpensive manner.

With the above and other objects in view this invention consists of the details of construction and combination of elements hereinafter set forth and then designated by the claims.

In order that those skilled in the art to which this invention appertains may understand how to make and use the same, I will describe its construction in detail, referring by numerals to the accompanying drawing forming a part hereof, in which:

Fig. 1 is a side elevation of a mop constructed in accordance with my invention.

Fig. 2 is a top plan view thereof with a portion of the handle broken away.

Fig. 3 is an enlarged cross sectional view of the detachable cap showing in dotted lines the manner of mounting the mop elements.

Fig. 4 is a plan view of the cap shown in Fig. 3 looking at the inner end.

Fig. 5 is a fragmentary bottom plan view of the handle unit.

Fig. 6 is a view of one of the mop elements laid out flat to show the stitching.

Fig. 7 is a side elevation of the device for use especially as a polisher.

In carrying out my invention as herein embodied 10 represents the handle unit consisting of a hollow or tubular shank 11 and a circular hollow head 12 open at one end. The interior of said head communicates with the bore of the shank through the elongated or substantially oblong flue 13 formed in the head with one end of said flue communicating directly with the shank

bore. On the perimeter of the head are formed a number of equally spaced lugs 14 which preferably have beveled thread engaging surfaces.

The detachable cap 15 includes a ring body 16 having an inwardly projecting rim edge 17 with passageways 18 through it spaced in the same relation as the lugs 14 and the inner or underneath surface of said ridge is inclined for short distances from the passageways as indicated at 19, Fig. 3. Beyond the rim ridge 17 is an internal inwardly projecting flange 20 which with said ridge 17 forms, at least in effect, a thread so that when the cap is assembled on the head of the handle unit said cap will be secured against accidental displacement. The bottom or outer end of the cap is provided with several parallel spaced bars 21 over which are folded the mop elements 22.

The mop elements may be of any suitable material but preferably each element is composed of a number of soft rope strands 23 laid side by side and sewn together by the stitches 24. A mop element is folded over each bar 21 by inserting opposite ends through the spaces between the bars and said ends of the mop element permitted to hang free. In order to prevent accidental displacement of the mop elements while providing for their removal, a knot 25 may be tied in one or more of the rope strands of each mop element. An excellent manner in which to do this is to tie a knot in both of the end rope strands of each mop element by nearly interengaging the two parts of each of said end strands outside of a bar 21. Portions of the knots thus formed will protrude beyond the perimeter of the cap, as shown in Fig. 2, and function as buffers to prevent the sides of the cap from coming in contact with the surface being operated upon and reducing to a minimum the chances of scratching or otherwise damaging said surface.

Generally the strands of the mop elements are long, as in Fig. 1, when the device is to be used truly as a mop and utilizing water or other liquid as the washing or cleaning medium, but may be much shorter, as in Fig. 7, when used as a polisher and employing an oil or some equivalent as the polishing medium. In all other respects the two devices are alike. Actually the two devices are made up by using one handle unit and two separate caps, each cap having its own mop elements of suitable length.

The handle unit, especially when used as an element of the mop assembly, is attached to a hose connected with a source of water supply.

Any desirable means may be employed for attaching the handle unit to the hose and for purposes of illustration I have shown a section of rubber tubing 26 on the outer end of the shank 11 as the coupling. In this case a hose nozzle can be inserted in the tubing and the water will flow into and through the handle unit.

In practice, when it is desired to wash a surface, the device is attached to a hose, as stated above, and the water turned on, and thereafter the mop is rubbed back and forth over the surface for loosening any dirt or other foreign matter. Since there is a constant supply of water passing through the mop, it is unnecessary to dip the mop into a pail of water from time to time. This not only eliminates time wasting operations but the cleansing element is always free from dirt. Further the water passing through the mop elements carries off all foreign substances which might otherwise cling thereto and keeps the mop fresh and clean. Also when mopping any surface which will shed water it is unnecessary to rinse such surfaces as this is done automatically by the water running over the surface from the mop.

A cake of soap, soap chips or other detergent in solid form may be placed in the chamber provided by the cooperation of the cap and head thus furnishing a supply of a cleaning agent which will be taken up by the water as it passes through the device.

After the mopping operations are completed the device can be removed from the hose and

the mop cap replaced by a polishing cap. The polisher can be used in a dry state or an oil or other fluid substance placed in the chamber within the polishing cap and the latter then mounted on the head of the handle unit. The device is now ready for the polishing operations and the fluid will be absorbed by the mop elements, after the manner of wicks, so as to maintain a constant supply at the outer ends of the 10 mop elements of the polisher.

Of course I do not wish to be limited to the exact details of construction herein shown and described as these may be varied within the scope of the appended claim without departing from the spirit of my invention.

Having thus described my invention, what I claim as new and useful is:

A mop and polisher consisting of a circular hollow head, a hollow shank formed with said head at substantially right angles to the axis of the head with the interiors of said shank and head in communication to allow a free flow of liquid through them, a cap detachably connected directly to the head, said cap including a circular body and spaced parallel bars, the spaces between the bars functioning as outlets for liquid flowing through the shank and head, and mop elements each comprising a plurality of rope strands, one of said mop elements folded over each bar and the folded portions of at least one rope strand of each mop element tied together to hold the mop elements in place.

ARVID E. ANDERSON.
